UNITED STATES PATENT OFFICE.

JOHN ARNOLD STREUN, OF SHERMAN, TEXAS, ASSIGNOR TO HARDWICKE-ETTER COMPANY, OF SHERMAN, TEXAS.

COTTON-CLEANING ASSEMBLY.

Application filed April 11, 1927. Serial No. 182,635.

My invention relates to cotton cleaners for use in eliminating dirt and trash from cotton before it is fed to the gin for separating the lint from the seed.

As is well known to those skilled in the art, the cotton picked in the field and delivered to the gin for ginning is received by the gin in various conditions, some being comparatively clean and open, while other cotton coming to the gin is mixed with a large amount of trash and may be only partly open and difficult to clean. It is, therefore, necessary in order to prepare the cotton for ginning that the cleaner which is employed for preparing the cotton should be so equipped as to handle all grades of cotton. This is made necessary through changes in weather or climate and through the fact that cotton comes from various localities to the gin and in different localities different grades of cotton are raised.

It is the principal object of my invention to provide an apparatus for cleaning cotton which is adapted to handle all grades and conditions of cotton delivered to the gin and to prepare the cotton for ginning with the least possible amount of handling, so that the cotton lint need not be damaged by excessive treatment and cleaning where such cleaning is not required.

It is a further object to provide the passage through which the cotton is carried on its way to the gin so equipped with valves and bypasses that the cotton may be directed through the proper channels with a minimum of manipulation on the part of the operator.

It is desired that the cleaning structure be simple and compact in arrangement and adapted to provide a maximum of cleaning action upon the cotton with the least possible amount of deterioration of the cotton due to handling.

The invention resides largely in the particular construction and arrangement of the parts and the connecting devices whereby my invention is made effective.

Referring for a more particular knowledge of the invention to the drawings accompanying the specification, Fig. 1 is a side view largely in elevation and illustrating my cleaning assembly with the sides of the housing removed and the operating pulleys omitted. Fig. 2 is a top plan view of the in-

vention; and Fig. 3 is a vertical section through the conveyer rolls employed in the hulling attachment and illustrating the arrangement of the brushing conveyers employed therewith. Like numerals of reference are employed to designate like parts in all the views.

The subject matter of the present application is somewhat similar to the disclosure in my prior co-pending application, Serial No. 56,614, filed September 16, 1925, which has resulted in Patent No. 1,630,638.

In carrying out my invention, it is first desired that the cotton be delivered to the cleaning devices in such manner as not to damage the cotton lint in any way and to remove therefrom some of the dust and dirt included with the cotton.

An upper housing 1, shown in Fig. 1, is employed above the cleaner. This housing is adapted to contain a cylindrical drum 2 with the outer wall thereof foraminated so as to allow the passage of air and dust therethrough from the outer side to the inner side. The drum is mounted upon the shaft 3 supported in the housing. The ends of the drum are connected with the suction fan or other means for creating an inward draught through the flue or pipe 4 leading to the housing. The cotton is thus drawn in through the said flue 4 and against the foraminated walls of the drum 2, so as to carry the dust and finer trash through the drum and out through the ends thereof.

Below the drum 2 is a rotatable shaft 5 having thereon rotatable valve or suction member 6. This valve is made up of a plurality of radial flights having at their outer ends a strip 7 of flexible material which is adapted to contact with the cylindrical walls 8 of the housing. It will be seen that when the cotton drops from the drum 2 above it upon this rotating valve, the suction from the drum 2 may not cause an inward draught past the valve due to the contact across the housing of the flights 6 and the flexible members 7 thereon. The cotton received between the adjacent flights will be carried around and delivered downwardly through an opening 9 into the chamber 10 below.

The chamber 10 contains a breaker roll 11 and a series of picker rolls 12 arranged in an upwardly inclined position above the breaker

roll. The said breaker roll has a series of teeth 13 thereon which are adapted to mesh with the teeth 14 upon a plate or "concave" secured to the frame of the housing 50. Thus 5 cotton delivered upon the breaker roll will be carried in the direction of rotation between the teeth 14 of the concave and unbroken bolls and burs will be broken up so that when carried upwardly along the screen 15 the trash 10 and dirt will be partially eliminated.

I have shown four of the picker rolls 12, arranged as previously stated, in a line inclined upwardly from the breaker roll. The screen 15 below the rolls is curved to conform 15 to the shape of the rolls so that the cotton will be rubbed and carried beneath the adjacent rolls and be eventually delivered through an opening, indicated at 16, at the upper end of the housing. The picker rolls 20 12 are cylindrical in shape and mounted on shafts 17 and journaled for rotation of the housing and having radial teeth 18 thereon to engage with and move the cotton along the screen below it. Below the rolls 11 and 12 25 is an inclined lower wall 19 on the housing leading to a trash flue 20 by means of which the dirt and trash passing the screen 15 may be conducted from the housing.

As the cotton is delivered through the opening 16, it passes into a chamber 21 which is a valve chamber. The two opposite openings 22 and 23 to this chamber are adapted to be closed by valves 24 and 25 respectively. These valves comprise plates extending the 30 full width of the housing and of a size to close the said openings 22 and 23, said valves being pivoted on rods 26 at their lower ends, said rods being adapted to be rotated so as to vary the position of the valves. When the two 35 valves are in erect position, as shown in Fig. 1, the cotton will pass directly downward upon a conveyer roll 27. If the valve 24 is left closed, as shown, and the valve 25 is moved into dotted line position, the cotton 40 will pass through the opening 23 into a chute 28. If, however, the valve 25 is left closed but the valve 24 is opened into dotted line position, the cotton may be delivered through the opening 22 into a chute 29.

If the cotton is particularly dirty and the 45 hulls thereon adherent to the cotton lint, the cotton after passing the cleaning rolls 12 will be delivered upon the conveyer 27. Referring to Fig. 2, it will be noted that the conveyer 27 carries the cotton through the side of the housing to the huller. The huller comprises an elongated rectangular frame 30, the sides of which form a housing for a plurality of conveyer rolls 31 and 32. I have shown 50 two of these rolls and as seen particularly in Fig. 3, these rolls have radial teeth 33 thereon extending in a spiral row for the full length of the housing 30. Beneath the upper roll 55 is a trough 34, which extends beneath the conveyer roll to a point spaced somewhat from

the end of the said roll, leaving an opening at 35 through which the cotton hulls may be delivered to the lower roll 32. Beneath the said roll 32 is a foraminated trough 36 over which the cotton is carried by the conveyer roll 32. It is to be understood, of course, that the rolls 31 and 32 are rotated in a direction to carry the cotton from left to right in the upper roll in Fig. 3 and from right to left on the roll 32, as shown in Fig. 75 3. Beneath the conveyer rolls 31 and 32 is a trash conveyer 37 of screw form adapted to carry the finer trash laterally from the housing.

Referring now to Fig. 1, the cotton delivered upon the upper rolls 31 will be carried along the face of a saw cylinder 38 closely adjacent thereto, the said saw cylinder having short teeth 39 thereon to engage with the lint upon the cotton and remove it from the hulls 85 and trash carried along the trough 34 of the conveyer roll. The cotton passing from the upper conveyer roll 31 to the lower roll 32 will be carried back again across the face of the saw cylinder 38 and by thus passing twice 90 across the face of the cylinder, all cotton lint will be removed from the hulls and trash and carried upwardly away upon the teeth of the saw cylinder.

Above the saw cylinder 38 is a baffle roll 95 40. This roll is adapted to rotate in the same direction as the saw cylinder. It has a series of radial flights 41 which extend to a line closely adjacent to the teeth of the saw cylinder and in rotating are adapted to contact with any hulls or bolls carried upwardly with the cotton lint and to knock the said bolls backwardly upon the conveyer roll 31. In this manner trash is prevented from being carried with the cotton lint away from the 105 hulls and trash upon the conveyer rolls.

The cotton is removed from the saw cylinder by the brushing roll 42, of ordinary construction, and is delivered by said brushing roll upon a conveyer 43.

The conveyer screw 43 extends the full length of the huller housing, as shown best in Fig. 2. It rotates in such a direction as to carry the cotton thus cleaned back again into the main housing of the cleaner. The 115 cotton is delivered by the conveyer screw 43 into a lower chamber 44, shown best in Fig. 1.

The chamber 44 is similar to the chamber 10 above. It has a series of picker rolls 45 therein arranged in a row inclined upwardly 120 from the point where the cotton is received, the upper roll being adapted to deliver the cotton into the lower end 46 of the chute 29. These picker rolls have a screen 47 below them similar in all respects to the screen 15 and the picker rolls are rotated in such direction as to carry the cotton from one roll to the next along the screen 47 so as to sift out from the cotton any dirt which may remain 125 in the lint. The cotton will thus be submitted 130

to a thorough cleaning before it is discharged into the chamber 46 upon a conveyer belt 48, which is understood as carrying the cotton lint to any one or more gins where it is to be 5 separated from the seed.

Where the valves 24 and 25 are manipulated to discharge the cotton into the chute 28, it will be seen that the cotton will be carried downwardly and discharged into the 10 chamber 44 where it will be submitted to the cleaning action of the rolls 45 and delivered to the conveyer without having to pass through the huller attachment. Where the valves are arranged to discharge the cotton 15 from the chamber 21 into the chute 29 directly, it will receive no cleaning other than that received in the chamber 10 under the action of the rolls 11 and 12 therein. It will thus be understood that the cotton entering through 20 the flue 4 to the feeder cleaner within the housing 1 will be submitted to a slight cleaning action in the housing 1, due to the suction from the housing, of dust and smaller trash. It will be delivered from this housing 25 into the chamber 10, where it will be broken up and carried over the screen 15 through the action of the picker rolls 12. The dust and trash, which is loose within the cotton, will be thus shaken and sifted from the 30 cotton and carried away through the outlet 20. If the cotton is in good condition and fairly clean, it may need no further cleaning than is obtained within this chamber, and if so, it may be discharged directly into the 35 chute 29 to the conveyer belt 48. If, however, the cotton needs some further cleaning, but does not necessarily have to pass through the huller, the valves 24 and 25 may be arranged to discharge the cotton through the chute 28 40 and thus submit it again to a similar cleaning action to that which was received in the chamber 10, by passing into the chamber 44 and to then pass up over the screen 47 for a further cleaning action. After which it will 45 be delivered to the conveyer belt. If, however, the cotton is to be submitted to the action of the huller it will be delivered to the conveyer 27 and pass through the hulling attachment in the manner already described. 50 In its passage through this portion of the machine, the hulls and trash will be thoroughly removed from the cotton and the cotton may then be delivered to the picker rolls 45 and the dirt and trash further removed in 55 its passage through this chamber.

The advantages of the device lie in the convenient arrangement by means of which the cotton may be cleaned selectively as becomes necessary due to the state of the cotton as it 60 enters the machine. It will be possible to submit all grades of cotton delivered to the machine to such cleaning action as may be necessary to fit it for the ginning operation. This may be done with a minimum manipulation 65 and effort on the part of the operator.

The further advantages of the device will be apparent to those skilled in the art.

What I claim as new and desire to protect by Letters Patent is:

1. In a cotton cleaner, the combination of 70 a feeder, a cleaning chamber, and a valve chamber arranged to successively receive the cotton, said valve chamber having open upper and lower ends, lateral opposite chutes opening into said chamber, providing three outlets from said chamber, a valve member for each chute pivoted at one end, and adapted to close said openings, whereby one opening is always unobstructed so that the cotton may be directed to various passages for treatment. 75

2. In a cotton cleaner, the combination of 80 a feeder, a cleaning chamber, and a valve chamber arranged to successively receive the cotton, said valve chamber having open upper and lower ends, lateral opposite chutes 85 opening into said chamber, a valve member to close each chute opening, said valves being so positioned as to control the opening and closing of the lower end of said valve chamber whenever either of said lateral chutes is 90 open whereby the cotton may be directed to various passages for treatment.

3. In a cotton cleaner, a cleaning chamber, means to feed cotton thereto, means in said cleaning chamber to move the cotton along a 95 foraminated screen, a valve chamber at the discharge end of said cleaning chamber, valves in the side walls of said valve chamber to control the direction of travel of the cotton, a cotton huller connected with said chamber, the opening thereto from the valve chamber being open when said valves are in closed position. 100

4. In a cotton cleaner, a housing, a cleaning device therein, a valve chamber adapted to receive cotton from said cleaning device, means to control the passage of cotton through said chamber, lateral chutes opening from said valve chamber, a laterally extending conveyer at the lower end of said chamber, a 110 saw cylinder therein, means to receive cotton from said conveyer and move it longitudinally of said saw cylinder, means to receive cotton from said cylinder, means to move said cotton back to said housing, and means to further clean said cotton. 115

5. In a cotton cleaner, a housing, a cleaning device therein, a valve chamber adapted to receive cotton from said cleaning device, said chamber having a bottom and two opposite 120 side openings therein, valves in said opposite side openings controlling the discharge of cotton to any of the three said openings, a conveyer belt, one of said openings leading thereto directly, a second cleaning device connected between another of said openings and said conveyer belt, and a huller and said second cleaner connected between the third of said openings and said belt, whereby the cotton may be selectively moved from said valve 125 130

chamber to said conveyor belt, may be further cleaned, or may be submitted to a hulling action as desired.

6. In a cotton cleaner, a series of cleaning rolls and a screen beneath them, in combination with a second set of similar cleaning rolls, a huller including a saw, means to move the cotton across the face of said saw and means to deliver the cotton therefrom to said second cleaning rolls, a conveyor, and means to selectively direct the cotton from said first series of cleaning rolls to said conveyor, or by way of said huller and said second cleaning rolls to said conveyor, or by way of said second cleaner alone to said conveyor, as desired.

7. In a cotton cleaner, a cleaning chamber, means to feed cotton thereto, an upwardly inclined foraminated screen, a plurality of picker rolls rotatable above said screen to advance the cotton along said screen, a valve chamber adjacent the said screen, said chamber having two side outlets and a bottom outlet, valves pivoted at the lower side of each side outlet to swing across said chamber and direct the cotton from said screen to any one of the three outlets, a conveyor belt at one of said outlets, a second cleaning chamber connected with one of said side outlets, and a huller attachment connected with another of said outlets, whereby said cotton may be controlled to obtain repeated cleanings or hullings as desired.

8. In a device of the character described including a housing, a series of cleaning rolls therein, means to feed cotton thereto, a valve chamber to which the cotton is delivered from said cleaning rolls, said chamber having open upper and lower ends and opposite valve controlled side openings, a chute leading to a distributor belt from one of said openings, a second chute leading indirectly to the dis-

tributer belt, cleaning devices disposed in said second chute, a chute leading from the bottom of said chamber to said second chute 45 cleaning devices, and a huller device disposed in said bottom chute.

9. In a cotton separator and cleaner, means to clean the cotton, means to break up the hulls, and means to selectively direct the cotton thru any one of three courses of treatment. 50

10. A cotton cleaning and separating device, including means whereby the cotton may be subjected to three types of treatment, and means to selectively direct the cotton thru 55 one of said first means.

11. In a device of the character described, a means to feed the cotton thereto, a cleaner thru which the cotton must pass, and means to receive the cotton from said cleaner 60 whereby it may be selectively directed to a conveyor belt, a cleaner or a huller.

12. In a device of the character described, a means to feed cotton thereto, a cleaner thru which the cotton must pass, and means to receive the cotton from said cleaner 65 whereby it may be selectively directed to a conveyor, a second cleaner, or a huller and said second cleaner.

13. In a cotton cleaner, a feeder, a cleaner, 70 means to receive the cotton from said cleaner including a valve chamber, a plurality of openings therefrom, and a pair of oppositely disposed valves operable to direct the cotton thru any one of said openings. 75

14. In a device of the character described, a feeder device, a series of breaker and cleaner rolls, means to receive the cotton from said rolls by gravity and selectively direct it to a belt, a cleaner, or a huller. 80

In testimony whereof I hereunto affix my signature this 4th day of April, A. D. 1927.

JOHN ARNOLD STREUN.
